HAND PUMP FOR SPRAYING LIQUIDS OR THE LIKE

Juel D. Clevenger, Raytown, Mo., assignor to Cook
Chemical Company, Kansas City, Mo., a corporation
of Missouri

Filed Nov. 20, 1967, Ser. No. 9,477

Term of patent 14 years

U.S. Cl. D9—276
Int. Cl. D9—99

Fig. 3.

Fig. 1.

Fig. 4.

Fig. 5.

Fig. 6.

FIGURE 1 is a side elevational view of a hand pump for spraying liquids or the like, showing my new design.

FIGURE 2 is a plan view;

FIG. 3 is a front elevational view;

FIG. 4 is a bottom view;

FIG. 5 is a rear elevational view; and

FIG. 6 is an elevational view showing the side opposite to FIG. 1, but with the pumping device unlocked and extended.

I claim:

The ornamental design for a hand pump for spraying liquids or the like, as shown.
